UNITED STATES PATENT OFFICE.

JOHN KELLY WEDGWORTH, OF CUBA, ALABAMA.

METAL RAIL-TIE.

1,399,909.

Specification of Letters Patent. Patented Dec. 13, 1921.

Application filed February 7, 1921. Serial No. 443,233.

To all whom it may concern:

Be it known that I, JOHN K. WEDGWORTH, a citizen of the United States, residing at Cuba, in the county of Sumter and State of Alabama, have invented certain new and useful Improvements in Metal Rail-Ties; and I do declare the following to be a full, clear, and exact description of the invention, such as will enable others skilled in the art to 10 which it appertains to make and use the same.

This invention relates to an improved metal rail tie which is designed to take the place of the ordinary wooden ties now used.

15 The principal object of the invention is to generally improve upon devices of this class by the provision of one of extreme simplicity and durability which embodies novel clamps or jaws for engaging the rail base 20 flange and novel means for retaining the clamps in effective engagement with the rails.

Another object of the invention is to provide a tie embodying a box-like body, in 25 which the aforesaid clamping jaws are slideable, there being arranged in this box novel adjustable retaining rods for the clamping jaws, the end rods being co-operative with the adjacent jaws and the intermediate rods 30 co-operative with the remaining jaws, all of said rods being easily and quickly removable to effect an adjustment whereby the grip of the jaws on the rails may be tightened or loosened when the rods are replaced.

35 The foregoing and other features and advantages of the invention will be apparent during the course of the following description.

In the accompanying drawings forming a 40 part of this specification and in which like numerals are employed to designate like parts throughout the same:

Figure 1 is a top plan view of a tie constructed in accordance with this invention, 45 the same being shown in use.

Fig. 2 is a central longitudinal vertical sectional view taken through the tie on the plane of the line 2—2 of Fig. 1.

Fig. 3 is a horizontal sectional view taken 50 on the plane of the line 3—3 of Fig. 2.

Fig. 4 is a detail perspective view of one of the clamping blocks.

In carrying out the invention, I make use 55 of a substantially rectangular box-like tie 1 which is, by preference, provided at its op-

posed sides with inturned flanges 2 on which the rails rest. Arranged in the tie and slideable therein are a plurality of clamping jaws or blocks 4 which are normally disposed beneath the flanges 2 and include spaced shoulders 5 on which said flanges rest to prevent the latter from being bent downwardly under the weight of the rails and passing trains. Each clamping jaw is provided in its inner face near its upper end with a recess 6 for 60 reception of the adjacent edge of the rail base as shown in the drawings, the reduced upper inwardly curved end 7 extending above the flanges 2 and engaging the upper face of the rail base. 70

As before intimated, I make use of a novel means for moving the jaws in engagement with the rails and retaining them in such position. The means by preference consists of a pair of relatively short rods 8 which are 75 designed to co-operate with the outer jaws and a pair of relatively long pivotally connected rods 9 adapted to co-act with the remaining jaws. The first named rods are provided at their outer ends with T-shaped 80 heads 10 receivable in seats 11 formed in the removable plates 12 which rest against the ends of the tie 1. The plates 12 are provided at their upper ends with hooks 13 to permit a suitable instrument to be engaged therewith for effecting a quick and easy removal of said plates. On the opposite ends of the rods 8 are detachable members 14 provided with T-shaped heads receivable in the adjacent correspondingly shaped seats or pockets 90 15 in the outer jaws. Now by referring to the longer rods 9, it will be seen that these rods, like the rods 8, are provided at their outer ends with the detachable members 14 having heads removably received in the cor 95 respondingly shaped seats 15 in the adjacent or inner clamping jaws. However, at their opposite ends a quick detachable knuckle joint 16 is provided. It will be seen that this construction provides a toggle which, when 100 its inner ends are forced below a certain horizontal line, will force the jaws with which they co-act into tight engagement with the rail base flanges. 125

With the foregoing construction, it will be seen that if the jaws should become loose, they may be moved closer together and in turn brought into tighter engagement with the rails by removing the rods 8 and 9 and properly adjusting these rods, or 110

better say, adjusting the members 14 which the rods carry. To effect an adjustment of these headed members on the rods 8, this may be done by engaging a suitable instrument with the hooks 13 of the plates 12 and exerting an upward pull so as to remove the rods 8. In actual practice, I have found that the toggle rod 9 can be more easily removed and I may suggest that these rods 10 will be removed first. However, just the reverse is true in replacing the rods. That is, it will be found better to place the rods 8 in position before placing the remaining rods 9 in position. By having all of the 15 rods adjustable, considerable movement of the jaws may be obtained to accommodate rails which are spaced far apart or close together. It is understood, that before the inner jaws are moved to operative position, 20 the rods 9 are inclined upwardly at their inner ends, that is, the knuckle joint 16 is at a higher position than shown in the drawing and in order to effect the proper clamping action of the inner jaws it is only necessary to force this knuckle joint downwardly 25 into engagement with the bottom of the tie. At this point, I again direct attention to the fact that the inwardly directed flanges 2 of the tie serve as seats for the rails and 30 the shoulders 5 of the clamping jaws serve in turn as supports for these flanges. This construction and arrangement is novel and obviates the necessity of employing special supporting means for the rails.

35 A careful consideration of the foregoing description taken in connection with the accompanying drawings is thought to be sufficient to enable persons skilled in the art to which the invention relates, to obtain a clear 40 understanding of the same. Therefore, a more detailed and lengthy description is deemed unnecessary.

Since the same results accomplished by this invention may be carried out in other 45 ways, I do not desire to be limited to the exact construction and arrangement herein shown and described, and I wish it to be understood that various minor changes in the shape, size, and arrangement of parts 50 may be resorted to so long as they do not depart from the spirit of the invention or the scope of the subjoined claims.

I claim:

1. A device of the class described comprising a tie including spaced vertical walls, 55 rails supported by and crossing said tie at right angles, inner and outer clamping jaws slidably between said walls and engaging the opposite sides of the rails, said inner jaws being equipped with seats, a toggle arranged between said inner jaws and having its opposite ends removably received

in said seats, and means for retaining the outer jaws in engagement with the rails.

2. The structure set forth in claim 1, said 65 toggle being made up of a pair of rods having their inner ends connected together by a detachable knuckle joint, and there being detachable members carried by these rods at their outer ends, said members being 70 equipped with T-shaped heads removably received in the seats in said inner jaws.

3. A device of the class described comprising a box-like tie, rails supported thereby, clamping jaws engaged with the 75 outer edges of the base flanges of said rails, being provided with seats, removable plates resting against the ends of said tie and provided in their inner faces with seats, adjustable rods disposed between the clamping 80 jaws and plates and having their ends received in said seats.

4. The structure specified in claim 3, said plates being provided with hooks at their upper ends, and said rods being formed at 85 one end with T-shaped heads receivable in the seats of said plates and being equipped at their opposite ends with detachable headed members removably received in the 90 seats of said clamping jaws.

5. A device of the class described comprising a box-like tie, rails disposed in spaced relationship and resting on the tie and crossing it at right angles, pairs of clamping jaws slidably disposed in said tie 95 between the sides and engageable with the opposite sides of the base flanges of said rails, each of said jaws being provided with a recess, removable abutments arranged in said tie and bearing against the closed ends 100 thereof, said abutments being formed in their inner faces with seats, a pair of relatively short adjustable rods arranged between the outer jaws of each pair and said abutments, said rods being formed at their opposite ends with heads removably received in said recesses and seats, and a pair of relatively long adjustable rods arranged between the inner jaws of each pair having heads received in the recesses therein 110 and having their inner ends connected by a detachable knuckle joint.

6. A device of the class described comprising a hollow metal tie including spaced longitudinal walls having turned supporting flanges at their upper edges, spaced rails resting on said flanges, and clamping means for the rails slidably between said walls and beneath said flanges, being equipped with spaced shoulders on which said flanges 120 rest.

In testimony whereof I have hereunto set my hand.

JOHN KELLY WEDGWORTH.
